UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

MACHINE FOR COOLING STEREOTYPE-PLATES.

1,269,240.

Specification of Letters Patent. Patented June 11, 1918.

Original application filed April 6, 1906, Serial No. 310,343. Divided and this application filed August 20, 1915, Serial No. 46,560. Renewed November 24, 1917. Serial No. 203,859.

To all whom it may concern:

Be it known that I, HENRY A. WISE WOOD, a citizen of the United States, residing at New York, in the county of New York and State of New York, have invented a new and useful Machine for Cooling Stereotype-Plates, of which the following is a specification.

This is a division of my pending application for patent for a machine for finishing and cooling stereotype plates, Serial No. 310,343, filed April 6, 1906.

This invention relates to the preparation of stereotype plates for printing, and especially to a cooling machine designed to take care of the product of several casting boxes.

Among the objects of the invention, broadly stated, is the provision of means for receiving articles or casts, especially curved stereotype printing plates, as they emerge or are discharged from a finishing mechanism, feeding them, cooling them and automatically setting into operation the several parts of the machine chiefly by the motion 25 of the plates themselves.

In order to provide a simple feed I have so constructed the machine as to make use of the force of gravity for this purpose.

While it is to be understood that the principles of my invention are applicable to the finishing of several different kinds of articles, I have illustrated the machine as applied to the finishing and cooling of curved stereotype plates.

Reference is to be had to the accompanying three sheets of drawings in which—

Figure 1 is a side elevation of a machine constructed in accordance with the principles of my invention.

Fig. 2 is a plan of a portion thereof, parts appearing in section, and

Fig. 3 is a sectional view on the line 3—3 of Fig. 2.

For an idea of the general nature of the invention, reference is to be had to Fig. 1 which shows a frame *a* provided with an inclined bed or runway *a'*, for carrying stereotype plates.

The machine is intended to be used chiefly in conjunction with a plurality of casting boxes, the product of which is placed by hand or otherwise on the upper end of the runway *a'*. These plates then move by

gravity down the run-way to finishing mechanism (not shown) by which their edges are first finished, then they enter another part *c* of the finishing mechanism in which their interior surfaces are shaved by a shaving blade *b*. From this point they pass to a cooler *d* and from that they move 60 out on a table *e* from which they are then removed by hand or otherwise.

It is to be observed that on account of the incline of the run-way and on account of the fact that it is provided with anti-friction devices shown as in the form of a series of rollers *2*, no positive feeding mechanism and no driving device for feeding the plates or other blanks is necessary. The incline of the bed is such that the plates are readily fed down by gravity when they rest freely on the rollers and if the rollers are held in stationary position and prevented from rotating, the plates are held and do not slide along the stationary surfaces of the 75 rollers.

When the plate is released from the shaver *b*, *c* it runs out on the rollers below it and into the cooler *d*. This cooler is in the form of a shell or arch having a chamber for receiving the plates or other articles to be operated upon. The outer wall of the shell is provided with a passage *3* having an opening for introducing water or other cooling fluid upon the outside of the plate. Inside the chamber is also located a plate *4* having a similar passage *5* for providing for cooling the inside of the stereotype plate. Both these passages are connected by pipes *6* with a supply pipe *7* having a valve or 90 cock *8*. With this cock is connected an arm *9*, link *10* and lever *11*. This lever is pivoted on the frame and is provided with dogs *12* located normally in the path of motion of a plate entering the cooler. When the 95 plate passes along the rollers and engages these dogs, it moves the lever in opposition to the force of a spring *13* which normally holds the valve *8* closed. This opens the valve so as to permit the cooling fluid to 100 enter both passages *3* and *5* and cool both sides of the plate as long as the plate remains in engagement with the dogs.

It is desirable to leave the plate in the cooler as long a time as is necessary for the 105 finishing of a plate in the shaver, conse-

quently I have provided movable stops 14, preferably pivotally mounted on a shaft 15. An arm 16 is provided for swinging the stops and this arm is connected by a link 17 with 5 a lever 18.

This lever is pivotally mounted on the frame and is provided with dogs 19 projecting into the path of an incoming plate. A spring 20 normally holds these parts in 10 the position shown in Fig. 1. When the dogs 19 are depressed by an incoming plate resting on them, the stops 14 are also depressed. The lever moves in opposition to the spring 20, and the plate in the cooler 15 slides out on the table *e* against a stationary stop 21. It will be seen, therefore, that each plate remains in the cooler until another plate is finished and delivered into a position to enter the cooler. If the operator desires to allow a plate to leave the cooler before another plate is delivered to it, or if 20 no more plates are to be delivered, he can manipulate the lever 18 by a hand-operated slide 22.

25 The water or other cooling fluid applied to the plates is collected in a receptacle 23 and may be discharged in any desired way.

The broad combination of a stereotype printing plate finishing mechanism and a 30 cooling device is claimed in my original application previously referred to, this divisional application being filed in pursuance to a requirement of the Patent Office that the details of the cooling mechanism be 35 specifically claimed in a divisional application.

While I have illustrated and described certain preferred embodiments of the invention, I am aware of the fact that many 40 modifications can be made therein by any person skilled in the art without departing from the scope of the invention as expressed in the claims. Therefore I do not wish to be limited to all the details of construction 45 herein shown and described, but what I do claim is:—

1. The combination with a stereotype plate cooling device having means for applying a cooling fluid to the surface of a 50 curved plate, of means for feeding a semi-cylindrical plate longitudinally to the cooling device.

2. The combination with a stereotype plate cooling device having means for applying a cooling fluid to the surface of a 55 curved plate, of means for feeding a plate longitudinally through the cooling device with a dwell of the plate therein.

3. The combination with a stereotype plate cooling device having means for applying a cooling fluid to a plate, of means for feeding a plate to the cooling device, means for arresting the plate therein, and means for delivering the plate therefrom.

35 4. In a machine of the character de-

scribed, the combination of an arch, a runway comprising a series of rollers arranged in alinement and extending into said arch for feeding plates thereto, and means in the arch for cooling a plate resting on said 70 rollers therein.

5. In a device of the character described, the combination of an arch or shell adapted to receive curved stereotype printing plates therein, a runway extending into and 75 through said arch comprising rollers for supporting printing plates, directing them into said arch, and receiving them therefrom, and means connected with said arch for cooling a printing plate therein. 80

6. In a device of the character described, the combination of an arch, a runway extending therethrough lengthwise adapted to receive printing plates thereon outside the arch at one end, feed them into the arch, 85 and out of the other end thereof, and means connected with said arch for cooling a plate therein.

7. In a device of the character described, the combination of an arch, a runway extending therethrough lengthwise adapted to receive printing plates thereon outside the arch at one end, feed them into the arch and out of the other end thereof, and means connected with said arch for cooling a plate 90 therein, comprising a water distributing device, a valve for controlling the admission of water to said water distributing device, and means adapted to be operated by a plate while entering the arch for opening said 100 valve.

8. In a device of the character described, the combination of an arch, a roller runway extending therethrough lengthwise adapted to receive printing plates thereon outside 105 the arch at one end, feed them into the arch and out of the other end thereof, and means connected with said arch for cooling a plate therein, comprising a water distributing device, a valve for controlling the admission 110 of water to said water distributing device, means adapted to be operated by a plate while entering the arch for opening said valve, and means for closing the valve when the plate leaves the arch. 115

9. In a device of the character described, the combination of a support for stereotype printing plates, a distributing device arranged over said support and adapted to distribute cooling fluid on the convex side 120 of a plate held thereon, and means adapted to be actuated by a plate when moved along said support for turning on the supply of cooling agent to said distributing device and thereafter turning it off. 125

10. In a device of the character described, the combination of a support for stereotype printing plates, a distributing device arranged adjacent to said support and adapted to distribute cooling fluid on the concave 130

side of a plate held thereon, and means adapted to be actuated by a plate when moved along said support for turning on the supply of cooling agent to said distributing device and thereafter turning it off.

11. In a device of the character described, the combination of a support for stereotype printing plates, distributing devices arranged near said support and adapted to distribute cooling fluid on the convex and concave sides of a plate held thereon, and means adapted to be actuated by a plate when moved along said support for turning on the supply of cooling agent to said distributing devices.

12. In a device of the character described, the combination of a plate finishing device, a cooling device for the plates in alinement therewith, a runway extending from the finishing device to the cooling device, means located in the path of the plate as it travels along said runway for automatically turning on a cooling fluid as the plate enters the cooling device, and for turning it off as the plate leaves the cooling device.

13. In a device of the character described, the combination of a device for finishing stereotype printing plates, a device for cooling said plates arranged in alinement with said finishing device, a runway for transferring plates from said finishing device to said cooling device, a trip device located in the path of the plate as it travels along said runway, and means controlled by said trip device for rendering the cooling device operative to cool a plate therein.

14. In a device of the character described, the combination of a device for finishing curved stereotype printing plates, a device for cooling said plates arranged in alinement with said finishing device, a runway extending from said finishing device to said cooling device, a trip device located in the path of the plate as it travels along said runway, and means controlled by said trip device for rendering the cooling device operative to cool a plate therein on both sides.

15. In a device of the character described, the combination of a device for finishing curved stereotype printing plates, a cooling device arranged in alinement therewith, a runway adapted to feed plates endwise from the finishing device to the cooling device, means in the cooling device for spraying both the convex and concave sides of a plate therein, and means located in the path of a plate as it travels along the runway for automatically turning water on when the plate enters the cooling device, and for turning it off as the plate leaves the cooling device.

16. In a device of the character described, the combination of finishing means, a cooling device, an inclined feeding device con-

nected the finishing means and cooling device and in line with both of them for feeding the plates by gravity from the finishing means to the cooling device, a movable stop for arresting the motion of the plates in the cooling device, and means for moving said stop into operative position when a plate approaches the cooling device, said means being operated by contact with a stereotype plate.

17. In a device of the character described, the combination of a frame having an inclined bed, a series of anti-friction rollers mounted along said bed and adapted to support stereotype plates and feed them by gravity, a finishing mechanism located in the path of the plates through the bed, a cooler located in the path of the plates through the bed, a receiving table located at the end of the bed and provided with rollers, said finishing mechanism, cooler, and receiving table being in alinement, and a stop at the end of said receiving table.

18. The combination of an inclined bed having rollers, finishing mechanism located adjacent to said bed, a cooling device, a movable stop for arresting the motion of objects through the cooling device, and means for moving said stop into operative position when an article approaches the cooling device from the finishing mechanism.

19. The combination of a cooling device, means for feeding stereotype plates thereto, a movable stop located adjacent to said cooling device, a dog located at the receiving end of said cooling device and adapted to be engaged by a plate when fed into the cooling device, and means connected with said dog for operating said stop.

20. In a device of the character described, the combination of a gravity feeding device, a cooling shell located in the path of a plate through said feeding device, and means for forcing a cooling fluid against the upper and lower sides of the plate while in the shell.

21. In a device of the character described, the combination of a feeding device, a shell located in the path of a plate through the feeding device, and means for forcing a cooling fluid against the upper and lower sides of the plate while in the shell.

22. In a stereotype plate finishing machine, the combination of an arch, means for introducing a cooling fluid into said arch, and means located in the path of the plates and operating upon the advance of a plate into said arch for automatically turning on a cooling fluid.

23. The combination of a plate receiving chamber having means for introducing a cooling fluid from two sides thereof, a pipe connected with said means, a valve for controlling the flow of fluid through said pipe, a dog located in the path of the plate enter-

- ing the chamber, and adapted to be operated thereby, and means connected with said dog for controlling said valve.
24. In a device of the character described, the combination of a frame having an inclined bed, a series of anti-friction rollers mounted along said bed and adapted to support stereotype plates and feed them by gravity, a cooler located in the path of the plates through the bed, a receiving table located at the end of the bed and provided with rollers, and a stop at the end of said receiving table.
25. In a device of the character described, the combination of an arch, means for introducing a cooling fluid into said arch, and means operating upon the advance of a plate into said arch for automatically turning on a cooling fluid.
26. In a device for cooling stereotype printing plates, the combination of means for guiding a stereotype plate to move longitudinally along an inclined path and independent means controlled by the plate for forcing a cooling fluid against the plate.
27. In a device for cooling stereotype plates, the combination of means for guiding a stereotype plate along a straight path, means for forcing a cooling fluid toward the plate, and means in position to be controlled by the plate as it moves along said path for turning on said cooling fluid.
28. In a device for cooling stereotype printing plates, the combination of means for discharging a cooling fluid, means for guiding a stereotype plate longitudinally along a path over said discharging means, and means in position to be operated by the plate as it moves along said path for controlling said discharging means.
29. In a device for cooling stereotype printing plates, the combination of a water supply valve, a cooling saddle, means for guiding a plate along a continuous path to and from the saddle, and means for keeping said valve open when the plate is over the saddle, and for closing it at all other times.
30. In a device of the character described, the combination of a device for applying a cooling fluid to the surface of a curved stereotype plate, and means for supporting and guiding said curved plate by its straight edges to said cooling device.
31. In a device of the character described, the combination with a frame, and a finishing means supported thereby, of a series of rollers carried by said frame adjacent to the discharge end of the finishing means for moving the plate along the frame after it is discharged from the finishing means, means located over said series of rollers for spraying the plate while it is located on said rollers, and means adapted to be engaged by the plate during its motion along the rollers for turning the water on and for thereafter turning it off.
32. In a device of the character described, the combination with a frame, of a finishing mechanism mounted on the frame, guiding means carried by the frame for supporting and guiding a plate from the finishing mechanism, a cooling arch arranged in the path of the plate along said guiding means, means in position to be actuated by the plates as they enter said arch for turning on cooling water, and means adapted to be operated by the plates as they leave the arch for turning off the cooling water.
33. In a device of the character described, the combination with a cooling fluid supply valve, of means for guiding a plate to move along a straight path adjacent thereto, and means controlled by the plate for automatically locking the valve to prevent the discharge of fluid whenever the plate is out of position to be cooled.
34. In a device of the character described, the combination with a supply valve for cooling fluid, of means for guiding a plate along a path adjacent thereto, and means controlled by the plate for automatically unlocking the valve so that it can open when the plate moves into position for being cooled.
35. In a device of the character described, the combination with a supply valve for cooling fluid, of means for guiding a plate along a path adjacent thereto, means controlled by the plate for automatically unlocking the valve so that it can open when the plate moves into position for being cooled, and means whereby said valve may be locked at all other times.
36. The combination with a cooling device for stereotype printing plates having means therein located in inclined position for receiving plates to be cooled, of means for guiding a plate down an incline into said cooling device by gravity.
37. The combination with a cooling device for stereotype printing plates having means therein located in inclined position for receiving plates to be cooled, of means for guiding a plate down an incline out of said cooling device by gravity.
38. A method of preparing stereotype printing plates which consists in finishing the plates, feeding them in a straight path, and while in position in line with their position while being finished, cooling them.
39. A method of preparing stereotype printing plates which consists in finishing the plates, feeding them forward in a straight path, and cooling them on the inside and outside simultaneously while they are in position in line with the position in which they were finished.
40. A method of preparing stereotype printing plates which consists in finishing

the plates, feeding them forward in a straight path, and cooling them on the inside and outside simultaneously while they are in position in line with the position in 5 which they were finished.

41. A method of preparing stereotype printing plates which consists in locating said plates on an incline and finishing them while in that position, feeding said plates forward by gravity in line with the position in 10 which they are while being finished, and cooling them while in the position parallel with that in which they were finished.

42. A method of preparing curved stereotype printing plates which consists in finishing the plates, feeding them forward in a straight path parallel to the position in 15 which they are located while being finished, and while still in that position, spraying water upon the plates to cool them.

43. A method of preparing curved stereotype printing plates which consists in finishing the plates, feeding them forward in a straight path parallel to the position in 20 which they are located while being finished and, while still in that position, stopping them in a position beyond that in which they were finished, and cooling them while still 25 in that position.

44. A method of preparing curved stereotype printing plates which consists in feeding them along in a straight path, stopping

them in a certain position, finishing them while stopped, feeding them forward, and cooling them while in stationary position. 35

45. A method of preparing curved stereotype printing plates which consists in feeding them along in a straight path, stopping them in a certain position, finishing them while stopped, feeding them forward, cooling them while in stationary position, finally 40 starting them forward again, shutting off the cooling means, and stopping the plates in an inclined position from which they may be removed by hand. 45

46. A method of preparing curved stereotype printing plates which consists in feeding them forward by gravity to a finishing device, stopping them therein, shaping the plates while in the finishing device, removing 50 the stopping means and allowing the plates to be fed forward out of the finishing device by gravity.

47. A method of preparing stereotype plates which consists in finishing the plates, 55 feeding them from the finishing device to a cooling device, and cooling them thereby.

In testimony whereof I have hereunto set my hand, in the presence of a subscribing witness.

HENRY A. WISE WOOD.
